UNITED STATES PATENT OFFICE.

GEORGE GORDON CAVE, OF FENNY STRATFORD, COUNTY OF BUCKS,
ENGLAND.

FALSE BOTTOM FOR MASH-TUNS.

SPECIFICATION forming part of Letters Patent No. 298,172, dated May 6, 1884.

Application filed June 25, 1883. Renewed April 10, 1884. (No model.) Patented in England October 11, 1881, No. 4,411.

To all whom it may concern:

Be it known that I, GEORGE GORDON CAVE, of Fenny Stratford, in the county of Bucks, England, master brewer, consulting brewer, and expert, have invented a certain new and Improved False Bottom for Mash-Tuns, Hop-Backs, or other Vessels for the Purpose of Drainage, (for which I have obtained British Letters Patent, No. 4,411;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification—that is to say:

My said invention—which relates to an improved false bottom for mash-tuns, hop-backs, or other vessels for the purpose of drainage—consists of a plate of cast-iron or other suitable metal or material, having holes cast or drilled therein, which holes on one side are taper or otherwise suitably shaped, and countersunk on the opposite side. In these holes cylinders or caps of copper or other suitable metal or material, closed at one end with a head perforated with a number of fine holes, and open at the other end, are inserted. These cylinders or caps, when of metal, may be secured in the holes by being swelled after insertion in the plate by the aid of a center-punch, the cylinders or caps, when of china or other inelastic material, being secured in the said holes by other suitable or equivalent means, such as by cement or hemp packing.

In order that my said invention may be properly understood, I now proceed more particularly to set forth the system, mode, or manner in or under which the same is or may be used or practically carried into effect, reference being had to the accompanying drawings, and to the letters and figures marked thereon—that is to say:

Figure 1 represents a sectional elevation of a portion of a cast-iron plate with some of the copper cylinders or caps inserted therein. Fig. 2 is a plan of the same. Fig. 3, drawn to a smaller scale, represents a plan of one of the segmental plates of a perforated false bot-

tom, showing the arrangement of a number of the cylinders or caps inserted within the perforations of the same. As shown more particularly in Fig. 1, the plate B of the false bottom is formed with holes therein. At one side of the plate each such hole is formed with a countersunk, b, and at the other side with a recess, b', to receive a flange on the cylinder or cap. The cylinders or caps A are formed of a corresponding shape, and are inserted within the said holes or perforations through the plate, the upper ends of the said caps being closed with heads a, perforated with a number of fine holes, a', and when placed *in situ*, with the flanges b' resting within the recesses b', each such cap, when of metal, is expanded into the countersunk part of the hole by applying a center-punch or equivalent expanding-instrument.

In lieu of constructing the caps A of copper, they may be formed of any other suitable metal or material. The plates B of the perforated false bottom also may be constructed of any other metal or material than cast-iron. For example, in applying my invention to draining in slate tanks and earthenware tanks for acid baths, the cylinders or caps may be formed of glass, china, porcelain, or other suitable material; and in lieu of inserting the said caps within the plate or plates of the false bottom, in the manner shown in the accompanying drawings, the caps may be provided with cement, asbestos, hemp, or other packing, in order to secure them within the holes of the said plate.

Having now described and particularly ascertained the nature of my said invention and the system, mode, or manner in or under which the same is to be used or practically carried into effect, I would observe that the invention is applicable to a variety of purposes where draining is required to be effected through fine perforations; and what I consider to be novel and original, and therefore claim as the invention secured to me by the hereinbefore in-part-recited Letters Patent, is—

1. The improved false bottom for mash-tuns, hop-backs, or other vessels for the purpose of drainage, constructed of plates, in the piercings or perforations of which plates caps or

cylinders A, with heads *a* having fine holes therein, are fitted, substantially as hereinbefore described.

2. In a false bottom for straining or draining purposes, the piercings or holes in the plate B, formed with countersink *b* and recess *b'*, for receiving the cylinders or caps A, formed of corresponding shape, and provided with heads *a*, with perforations *a'*, constructed and

operating as and for the purpose herein set forth, and shown by the drawings.

In testimony whereof I, the said GEORGE GORDON CAVE, have hereto set my hand.

GEORGE GORDON CAVE.
